UNITED STATES PATENT OFFICE.

ROBERT WESENER AND WILLIAM WESENER, OF CLEVELAND, WISCONSIN.

RECEPTACLE.

No. 918,405.

Specification of Letters Patent.

Patented April 13, 1909.

Application filed June 12, 1908. Serial No. 433,242.

To all whom it may concern:

Be it known that we, ROBERT WESENER and WILLIAM WESENER, citizens of the United States, residing at Cleveland, in the county 5 of Manitowoc and State of Wisconsin, have invented certain new and useful Improvements in Receptacles, of which the following is a specification.

This invention relates to apparatus which 10 are adapted to supply poultry and small live stock with drinking water and refers to what are known as poultry fountains.

An object of this invention is to provide a cover of special structure which when applied 15 hermetically seals the can.

Another object of the invention is the provision of means by which the fountain can be carried from place to place and hung against a post, a fence or the like.

20 The invention has for a further object a poultry fountain which is simple in construction and in the number of its parts so that it can be readily handled.

Other objects and advantages will be apparent 25 from the following description and it will be understood that changes in the specific structure shown and described may be made within the scope of the claims and that any suitable materials may be used without departing from the spirit of the invention.

In the drawing forming a portion of this 30 specification, and in which like numerals of reference indicate similar parts in the several views, Figure 1 is a side elevation of the complete device, Fig. 2 is a vertical section of the same, Fig. 3 is a top plan view, Fig. 4 is a top plan view of the cover detached, Fig. 5 is a sectional view of the cover and its 35 parts disengaged from one another.

Referring to the drawings, 10 designates a receptacle of preferably cylindrical form and constructed from sheet metal or the like which is provided with a faucet 11 which is 40 disposed at its lower end upon which is adapted to be hung a drinking receptacle 12. At the upper end of the receptacle 10 are positioned cleats 13 which extend upwardly and outwardly and support a bail 14 which is provided with a suitable hand grasp 15. The receptacle 10 is provided with a central aperture 17 around which is struck up a flange 18. Upon the upper face of the can 10 an annulus 19 is secured by 45 means of the flange 18. The annulus 19 is provided with diametrically disposed arms

20 which pivotally support links 21. The annulus 19 upon its upper surface is provided with a boss 22 and a washer 23. A cover 24 is adapted to be placed upon the annulus 19 60 over the opening 17 of the top. The cover 24 is provided with an upwardly extending arm 25 which carries a cotter pin 26 at its upper extremity. Disposed upon the upper face of the cover 24 is a plate 27 which is 65 centrally apertured and which is adapted to be engaged over the arm 25. The plate 27 is provided with a laterally extending arm 28 by means of which the plate 27 is adapted to be rotated about the arm 25. 70

Upon the upper face of the plate 27 two arcuate cams 29 and 30 are positioned which are adapted to engage the inner ends of arms 31 positioned diametrically opposite upon the edges of a disk 32 which is centrally 75 apertured and is adapted to be engaged over the arm 25 and secured thereon by the cotter pin 26. The arms 31 are of such a thickness and width that they engage the upper surface of the plate 27 while the same is rotated, 80 through a small arc without engagement with the cams 29 and 30. The lower end of the faucet 11 extends down into the receptacle 12 below the level of the water. By this arrangement the amount of water in the 85 receptacle 12 will be kept at a constant level as it is drawn by the fowls or small live stock.

In removing and securing the cover 24 90 the following operations are necessary: 90 When it is desired to close the receptacle 10 the cover 24 is placed upon the annulus 19 over the aperture 17 in the top of the receptacle, the plate 27 is then positioned over the arm 25 and the disk 32 is mounted over 95 the plate 27 and is secured in position by means of the cotter pin 26. The links 21 are then drawn upwardly over the arms 31 and the arm 28 is operated to turn the plate 27 and the binding of the links 21 upon the 100 arms 31 causes the tightening of the cover 24. The washer 23 is positioned between the annulus 19 and the cover 24. By the use of this device it is readily seen that air cannot be admitted to the can 10. In order to remove the cover 24 all that is necessary is to reverse the motion of the arm 28 and to disengage the cams 29 and 30 from the inner ends of the arms 31. This action releases the links 21 when they draw down on the 110 top and admit of the cover 24 being removed from the can 10.

What is claimed is:

1. A device of the character described comprising a body portion having an aperture in the top thereof, an annulus mounted 5 about said aperture on said body portion, arms radially extended from said annulus, links mounted through said arms, a cover for said body portion, a disk supported by said cover, arms carried by said disk, said arms adapted to be engaged by said links, and a cam carried by said cover, said cam adapted to raise said disk and to bind said links.
2. In a device of the character described 15 the combination with a body portion of a closure therefor, said closure comprising an annulus carried by said body, diametrically opposed arms extending therefrom, links carried by said arms, a cover adapted to be positioned over said aperture upon said annulus, a washer adapted to be interposed be- 20

tween said cover and said annulus, an upwardly extending arm from the upper face of said cover, a rotatably mounted plate disposed about said arm, a laterally positioned 25 arm on said plate, cams carried upon the upper face of said plate, a disk mounted upon the upper end of said cover arm, arms projecting laterally from said disk, said arms adapted to be engaged by said cams 30 for the purpose of raising said disk, said links adapted to engage over said disk arms and to be secured thereto by the raising of said disk.

In testimony whereof we affix our signatures, in presence of two witnesses.

ROBT. WESENER.
WM. WESENER.
